UNITED STATES PATENT OFFICE.

WILLIAM G. BURDICK, OF ROCHELLE, ILLINOIS.

PISTON-RING.

1,187,811.

Specification of Letters Patent. Patented June 20, 1916.

Application filed March 13, 1916. Serial No. 83,903.

To all whom it may concern:

Be it known that I, WILLIAM G. BURDICK, a citizen of the United States, residing at Rochelle, in the county of Ogle and State 5 of Illinois, have invented certain new and useful Improvements in Piston-Rings; and I do declare the following to be a full, clear, and exact description of the invention, such as will enable others skilled in the art to 10 which it appertains to make and use the same.

This invention relates to certain new and useful improvements in packing rings for pistons.

15 The invention is designed more particularly for use in connection with pistons of explosive gas engines, although it will be obvious from the consideration of the detailed description and drawings that it is 20 equally applicable to other forms of pistons and similar constructions where metallic packing is used.

As is well known to those familiar with explosive and expansion engines, where a 25 metallic packing ring is required, the piston is circumferentially grooved at one or more points and a split packing ring fitted snugly within the groove, with its meeting ends sufficiently separated to permit expansion of the ring under heating. The opening, however, provides a path for the gases or fluids from one side of the piston to the other, which steadily increases with wear, thereby materially lowering the efficiency 30 of the engine and ultimately requiring the repairing of the piston.

Various means have been adopted or suggested for obviating this difficulty, one of the most common of which is the use of a 40 plurality of rings in which the splits or openings therein are located as far as possible on opposite sides of the piston. While this overcomes the difficulty to some extent, the construction permits the fluids to pass 45 the first ring, and by traversing the groove to the other side of the piston, escape through the opening of the second ring. It has been also proposed to join or bridge the ends of the ring in various ways and by different devices to prevent the passage of 50 fluids through the cut.

This invention belongs to the latter class of ring construction, and consists of certain novel features of construction, and the combination and arrangement of parts as will 55 be hereinafter fully described and claimed.

The accompanying drawings illustrate the preferred form of the invention, wherein similar reference characters designate like parts throughout the several views.

Figure 1 is a perspective view of a piston ring constructed in accordance with this invention, showing the coupler detached from the ring proper; Fig. 2 is a side elevation of a portion of the same showing the coupler 60 inserted between the ends of the ring; Fig. 3 is a plan view of a portion of the same; Fig. 4 is a sectional view taken on the plane of the line 4-4 of Fig. 3; and Fig. 5 is a similar sectional view, showing the coupler 65 removed.

In the embodiment illustrated, the reference numeral 1 designates a split metallic piston packing ring, from the free ends of which extend spaced lugs 2. These lugs 2 70 extend circumferentially relative to said ring and are rabbeted at the outer sides of their free ends as at 3.

Disposed between the lugs 2 and extending circumferentially from the ends of the ring 1 are V-shaped tongues 4, the latter being disposed adjacent the inner sides of said ring and having their outer sides arranged concentrically relative to the outer sides or periphery of the ring, as clearly shown by 75 the drawings, while the inner sides of the tongues 4 are arranged angularly with respect to the inner side of the ring.

The split or cut between the ends of the ring 1 is bridged by a coupler 5, which is 80 received between the aforesaid lugs 2 and provided with V-shaped notches 6 at its opposite ends. These notches 6 are disposed adjacent the inner side of the coupler and are inclined outwardly from their outer to 85 their inner ends to receive the V-shaped tongues 4 carried by the ends of the ring 1, this construction providing a very snug fit, and at the same time firmly holding the coupler in place when the ring is contracted. 90 The outer sides of the tongues 4 bear against the outer walls of the notches 6 while the inner walls of the notches rest against the inner angularly arranged sides of the 95 tongues and hold the outer side of the coupler flush with the outer side of the ring, the inner side of the coupler being then consequently held flush with the inner side of the ring owing to the fact that the coupler and ring are equal in thickness.

100 As shown by the drawings, the coupler 5 is substantially one-third the width of the 110

piston ring 1, with the exception of its intermediate outer side, which is provided with laterally extending wings 7. These wings 7 extend outwardly from the edges 5 of the coupler and have their inner sides spaced from the inner side of the coupler, whereby they are seated upon the aforesaid rabbeted sides 3 of the lugs 2.

The ring is assembled with the piston in 10 substantially the usual manner, the bridge piece or coupler, however, being adjusted to the ends of the rings after it is slipped into the groove provided for it in the piston.

It will be seen that with a ring constructed 15 in accordance with this invention, leakage directly past the opening or around the packing of the ring is prevented, and the coupler is maintained in proper contact with the wall of the cylinder by the pressure of 20 the ring ends, and is therefore independent of the gas pressure within the cylinder.

From the foregoing description, taken in connection with the accompanying drawings, the advantages and operation of the 25 device will be readily understood without a more extended explanation.

It is also to be understood that the accompanying drawings merely illustrate one manner in which the invention may be constructed, and as various minor changes in 30 form and proportion may be resorted to without departing from the spirit of the invention, I do not wish to limit myself to the construction herein shown and described 35 other than that set forth in the appended claims.

I claim:

1. A device of the class described comprising a split ring having spaced lugs extending circumferentially from the ends thereof, V-shaped tongues disposed between said lugs and extending circumferentially from the ends of said ring, said tongues being disposed adjacent the inner side of said 40 ring and having their outer sides arranged concentrically relative to the outer side of the same, the inner sides of said tongues being arranged angularly to the inner side of said ring, and a coupler received between said lugs and having its inner and outer 45 sides flush with the inner and outer sides respectively of said ring, said coupler being provided with V-shaped notches at its opposite ends for receiving said tongues, said notches being disposed adjacent the inner 55 side of said coupler and inclined outwardly from their outer to their inner ends.

2. A device of the class described comprising a split ring having spaced lugs extending circumferentially from the ends thereof, the outer sides of said lugs being rabbeted, tongues disposed between said lugs and extending circumferentially from the ends of said ring, a coupler received between said lugs and provided with notches 60 at its opposite ends for receiving said tongues, and wings extending laterally from the edges of the intermediate portion of said coupler and along the outer side thereof, said wings being seated on the rabbeted sides of said lugs.

3. A device of the class described comprising a split ring having spaced lugs extending circumferentially from the ends thereof, the outer sides of said lugs being rabbeted, V-shaped tongues disposed between said lugs and extending circumferentially from the ends of said ring, said tongues being disposed adjacent the inner sides of 75 said ring and having their outer sides arranged concentrically relative to the outer sides of said ring, a coupler received between said lugs and provided with V-shaped notches at its opposite ends for receiving said tongues, said notches being disposed adjacent the inner side of said coupler and inclined outwardly from their outer to their inner ends, and wings extending laterally from the edges of the intermediate portion of said coupler and along the outer side 80 thereof, said wings being seated on the rabbeted sides of said lugs.

In testimony whereof I have hereunto set my hand in presence of two subscribing witnesses.

WILLIAM G. BURDICK.
